UNITED STATES PATENT OFFICE

WILLIAM KREIELSHEIMER, OF NEW YORK, N. Y.

DESIGN FOR A MUFFLER OR SIMILAR ARTICLE

Application filed January 8, 1931. Serial No. 38,240. Term of patent 3½ years.

To all whom it may concern:

Be it known that I, WILLIAM KREIELSHEIMER, a citizen of the United States, residing in Queens County, city of New York, State of New York, whose post-office address is 60 Leonard Street, city of New York, county of New York, and State of New York, have invented a new, original, and ornamental Design for a Muffler or Similar Article, of which the following is a specification, reference being had to the accompanying drawing, forming part thereof.

The figure of the drawing is a plan view of approximately a quarter section of a muf-

fler, or similar article, showing my new design.

The dot and dash lines shown in the drawing define a one quarter section of the motif constituting the complete design. The other three sections of the design are identical and continue in proper relation to the section shown.

I claim:

The ornamental design for a muffler or similar article substantially as shown and described.

WILLIAM KREIELSHEIMER.
